UNITED STATES PATENT OFFICE.

PETER NYHOLM, OF EDGEWOOD, WASHINGTON.

REVOLVING-LEAF EXTENSION TABLE.

Application filed February 21, 1925. Serial No. 10,874.

My invention relates to filler leaves for extension tables which are of such construction that they are adapted to be stored, when not in use, under the permanent table top whereby when the table is extended the filler leaf is exposed and in position to be revolved and placed into position as an additional table top surface.

My invention consists in means secured to the underface of the permanent table top sections in combination with means cooperating therewith to revolvably support a filler leaf on the table; my invention consists further of the parts and combination of parts as will be hereinafter more fully set forth.

In the drawings:

Figure 1 is a top plan view of the table embodying my invention with the filler leaf in operative position.

Figure 2 is a bottom plan view of a table top with my invention attached thereto.

Figure 3 is a cross sectional view through the table top showing the filler leaf in stored position.

Figure 4 is a view similar to Figure 3 showing the filler leaf swung to operative position.

Figure 5 is a view showing the bracket for the leaf in end and side elevations.

Figure 6 is a top plan view of the runway.

Figure 7 is an end view of the same.

Figure 8 is a side elevation of a slide.

Figure 9 is a bottom plan view of a table top showing another embodiment of my invention.

Figure 10 is a detail view.

The reference numerals 1 and 2 designate the permanent end top sections of an extension table which are connected to the slides 3, which slides in turn are connected to the slides 4.

It is frequently necessary to increase the seating capacity of a table and the usual custom has been to have extra leaves stored in a separate box, which leaves must be brought to the table for use. In accordance with my invention the leaves are stored permanently under the table top, which broad idea is, of course, old. My invention resides in the particular means of mounting and storing the filler leaves under the table top.

The reference numeral 5 designates the filler leaf which is formed in two sections which are secured together by means of hinges 6 of any approved construction. To

the underface of the end sections 1 and 2 of the table I permanently secure a slideway 7 clearly illustrated in Figures 6 and 7 of the drawing from which it will be seen that these slideways 7 have an underface groove which is formed by rebending the edges of the metal from which the slideway is formed. The filler leaf is provided with brackets 8 for perforations 9 in which a rod 10 is loosely mounted. The ends of the rod 10 are mounted in the perforations of the slides 12, said slides having laterally extending flanges 13 which are adapted to slide in the undercut grooves of the slideways 7 so that when the table top ends 1 and 2 are spaced from each other, as shown in Figure 2, the slides 13 move freely in the slideway 7, a suitable stop being on each end of the rod 10 to prevent disengagement of the rod from the slides as will be readily understood. This separation of the table top sections 1 and 2 exposes the filler leaf 5 which is revolved on the rod 10 to the position shown in Figure 4 whereupon the uppermost section of the filler leaf is moved on the hinges 6 whereby the filler leaf bridges the distance between the side edges of the table as clearly shown in Figure 1. When the leaves are in stored position the free ends 85 are stored by means of the bracket 14 which is preferably secured to the middle slide 4.

In the embodiment illustrated in Figures 9 and 10 the slideways 15 are of the same construction as the slideways 7. In Figure 9 the filler leaf 16 is provided with slideways 17 on its underface in alinement with the slideways 15. A slide comprising arms 16 and 17 is slidably mounted in the slideways 15, and the slide comprising the arms 18 and 19 is slidably mounted in the slides 17 on the filler leaf, and when the parts are assembled the arms 7 of one slide is pivotally secured at 20 to the arm 18 of the slide mounted on the filler leaf whereby the filler leaf may be sustained in stored position under the permanent table top or may be revolved to operative position as shown in Figure 1. In connection with this embodiment the bracket 14, of course, will be used to support the filler leaf in inoperative position as illustrated in Figure 3.

My invention may be attached to an extension table of any construction and the parts embodying my attachment are so simple that they can be manufactured and put on the market at a minimum price.

By my invention I am enabled to materially simplify the storage of filler leaves under the permanent table tops of an extension table.

5 I am aware that changes may be made in the details of construction without departing from the scope of the appended claims.

What I claim is:

10 1. In an extension table, the combination with the permanent top sections, a slideway secured to the underface of each section, a filler leaf, slideways secured to the underface of said leaf, a slide mounted in each of said slideways and means pivotally connecting 15 the slide of the filler leaf to the slides of the top sections.

20 2. In an extension table, the combination with the permanent top sections, a slideway secured to the underface of each section, a slide in each of said slideways, a filler leaf, a pair of independent slideways secured to the underface of said leaf, an independent slide in each of the leaf slideways, the outer ends of the slides of the leaf overlapping

and pivotally connected to the outer ends 25 of the slides on said sections.

3. In an extension table, the combination with the permanent top sections, a slideway secured to the underface of each of said sections, a filler leaf, slideways secured to the underface of said leaf in alinement with each other, an independent slide mounted in each of said slideways, with its outer end bent at right angles, and means pivotally connecting the bent end of slides on the table 30 sections with the bent ends of the slides on the leaf.

4. A support for a filler leaf for extension tables, comprising four slideways, and a slide in each of said slideways, one end of 40 each slide being bent at right angles, and means pivotally connecting the right angle end of one slide to the right angle end of another slide.

In testimony whereof I affix my signature.

PETER NYHOLM.
